UNITED STATES PATENT OFFICE.

ANDRO AUGUSTYN, OF EAST DERBY, CONNECTICUT.

COMBINATION-LOCK.

1,391,662.

Specification of Letters Patent. Patented Sept. 27, 1921.

Application filed October 4, 1917. Serial No. 194,680.

To all whom it may concern:

Be it known that I, ANDRO AUGUSTYN, subject of the Emperor of Austria, resident of East Derby, county of New Haven, and 5 State of Connecticut, have invented certain new and useful Improvements in Combination-Locks, of which the following is a specification.

This invention relates to improvements in 10 locks, such as are adapted to be applied to doors, and has as its principal object the provision of means whereby the bolts are doubly secured when in an engaged position.

A further object is to provide a lock 15 adapted to be manually operated without the use of a key, and finally, to provide a lock which is considered to be burglar proof.

These and other like objects are attained by the novel construction and combination 20 of parts hereafter described and shown in the accompanying drawings, forming a material part of this disclosure, and in which—

Figure 1 is a top plan view of a lock showing its application to a door.

25 Fig. 2 is a similar plan view, the cover plate being removed.

Fig. 3 is a vertical sectional view taken on line 3—3 of Fig. 7.

Fig. 4 is a similar view to Fig. 3, showing 30 the parts in a different position.

Fig. 5 is another vertical sectional view, taken in a different plane, on line 5—5 of Fig. 3.

Fig. 6 is a similar view of the same, the 35 section being taken on line 6—6 of Fig. 4, and

Fig. 7 is a longitudinal sectional view taken substantially on line 7—7 of Fig. 6.

In the several drawings, the numeral 10 40 designates the door or movable part, and 11 the jamb or door casing, in which is set the keeper plate 12, held in position by screws in the ordinary manner, and provided with suitable openings for the reception of a pair 45 of cylindrical bolts 14, both being rigidly secured to a rectangular sliding bar 15 operable transversely of the casing, and having at its opposite end a raised arcuately recessed head 16, contactable with which is the 50 convexly curved end of a lever 18, mounted on the squared portion of a spindle 19.

Also secured upon the spindle 19, is a coiled spring 20, adapted to press the lever inwardly or against the bar 15, the spindle 55 also having secured upon it a dog 22, the point of which is contactable with a face

cam 23, so as to be operated by it as it is rotated, the same being rigidly mounted upon a spindle 24, the outer end of which is engaged with a sleeve 25, having a mark 26 60 registerable with a circular row of graduations 27 as can best be seen in Fig. 1. Thus the position of the cam will be evident to a person from the exterior of the lock.

Affixed upon the spindle 24, adjacent to 65 the inner cover of the lock casing, is a spur gear 30 meshing with a mating gear 31, formed with a sleeve 32, journaled upon another spindle 33, and having a protruding sleeve 34, pinned or keyed to the operating 70 knob 35, by means of which the gears are rotated and by them the cam, causing the dog 22, to turn the spindle 19, through a small arc of a circle, and as the lever 18, is resting against the end of the bar 15, which 75 is pressed in this direction by means of the springs 21, and is actuating the bolts 14, thus causing engagement or disengagement with the keeper 12.

The bar 15 is provided with a slot 37, 80 having an angular end 38, receptive of a locking pin 40, the same being rigidly secured at its inner end to a spring engaging lever 41, pivoted on the pin 42, and having its opposite end 43, engaged with a flattened 85 part of the spindle 33 and resting against a collar on the inner end of the spindle 33, so that as the same is caused to slide in the sleeve 34, by means of the knob 45, the lower end 43 of the lever 41 is operated and 90 through it the pin 40 is extended or retracted through an opening in the lock casing in an obvious manner.

Extending from the opposite side of the lever 41, to that of the pin 40, is a stem 47, 95 having a T-shaped head 48, engageable in the opening 49 made through the cam 23 and from which extends an arcuate slot 50, adapted to receive the stem 47, so that as the cam is turned toward the left in Fig. 2, 100 100 the pin 40 is held within the angular end 38 of slot 37 in bar 15, because the stem 47 will then be at the end of the arcuate slot 50.

Arranged to slide longitudinally of the lock, transversely of the bolt element 15, is a 105 plate 52, containing a longitudinal slot 53, through which the pin 40 also operates.

Movement is transmitted to the plate 52, by direct contact with another slidably arranged plate 55, in which is formed a 110 series of perforations 56, acting in the manner of a rack and engageable by the pro-

jecting pins 58, of a disk 59 operating as a pinion and secured to the inner end 60, of the sliding spindle 33, so that as the spindle is turned by the knob 45, the plates 55 and 52, are caused to move rectilinearly, the extreme front end of the plate 55 being engageable in a slot 62, formed in the edge of the bar 15, so as to hold the latter in an outward position.

10 In operation, it is assumed that the bolts are in the unlocked position as shown in Fig. 3 in which the pin 40 is held in the longitudinal slot 53 of plate 52 and the horizontal branch 37 of the angular slot in the bar 15, while the springs 21 press this bar as far to the right as possible by the engagement of the head 16 with lever 18. If it is now desired to lock the lock, the knob 35 is turned toward the right to rotate the 15 gears in order to bring the cam 23 and its slot 49 in alinement with the head 48 of the bolt or pin 40 which position is indicated by the mark 26, on sleeve 25 which at this time is in register with a certain number 20 of the graduations 27.

When now the knob 45 is pushed inwardly it will result in pulling the pin 40 back, and the spring impelled lever 18 will press the plate 15 and bolts 14 into engagement with 25 the keeper against the action of springs 21. The pin 40 will then enter the vertical branch 38 of the angular slot in the bar 15. When now the knob 35 is turned toward the left, the gears will be rotated and bring 30 the cam slot 49 out of alinement with the head 48 of the pin 40 which is thus held in this position. In order to further lock 35 the plate 15 the knob 45 must be rotated to

the right again, which will bring the sliding plate 55 in engagement with the slot 40 62 of the bar 15.

When it is desired to unlock the lock, the knob 45 is turned to the left in order to disengage the sliding plate 55 from the slot 62 in plate 15 and knob 35 is rotated toward the right to bring the cam slot 49 again in alinement with the head 48 of the pin 40, which position is indicated by the mark 26 on sleeve 25, coming in register with the predetermined number of the graduations 27. Then the knob 45 is drawn out which 50 operation will actuate the lever 41 to press pin 40 out of the cam slot and its other end will drop into the horizontal branch 37 of the slot in bar 15 which in the meantime has 55 been moved backward by the springs 21 so that the bolts 14 will leave their keepers and assume the position shown in Fig. 3.

Having thus described my invention what I claim as new and desire to secure by Letters Patent, is:

In a lock, the combination with a casing and a keeper therefor, of a lock bar carrying bolt engageable with said keeper, said lock bar being slidably transversely in said casing, a plate slidable longitudinally of said casing engageable with said lock bar, said lock bar having a recess, a sliding plate having a part engageable within said recess, and means for operating said sliding plate, whereby said lock bar may be held in an outward position.

In testimony whereof I have affixed my signature.

ANDRO AUGUSTYN.
